HARRY E. SQUIRE, OF OAKLAND, CALIFORNIA, ASSIGNOR OF ONE-HALF TO FRANK G. WHITE, OF SAN FRANCISCO, CALIFORNIA

REENFORCED CONCRETE PILE CONSTRUCTION

Application filed November 1, 1927. Serial No. 230,247.

My invention relates to reenforced concrete pile constructions in which the piles are driven for the purpose of supporting a deck or platform of concrete or other material, the elevation of which is fixed.

In driving piles it is impracticable and uneconomical to bring the top ends to any predetermined elevation above the bottom or above the water level. In many instances it is almost impossible to drive a pile within two or three feet of a predetermined elevation. It has been the practice, heretofore, to cut off the piles after driving at the exact elevation required for placing the deck. In case of concrete piles, the cutting itself is not only expensive but in addition it delays the work so as to greatly increase the cost of pile driving.

Another disadvantage in the methods now used in pile driving, is that due to hidden obstructions in the bed in which they are driven, they cannot be properly centered. This being the case it is almost impossible to predetermine any point at which a deck or platform is to be supported by the piles, before the piles are actually driven.

It is a well known fact that concrete piles exposed to sea water deteriorate very slowly, if at all, below the water level, and that the deterioration is most rapid in the length of the pile immediately above the water level which is exposed to the air and to the splashing of the water. It is evident that if the pile is protected in the belt immediately above the low water level, the life of the pile will be greatly prolonged.

In general it is the object of my invention to provide a telescoping cap or sleeve at the upper end of a driven pile which can be adjusted for height, so that the top of the cap or sleeve can be quickly and economically set to the exact elevation required for supporting the deck or platform.

Another object of my invention is to provide a telescopicably adjustable pile, the sections of which are provided with sufficient play or looseness with respect to each other, so as to allow the upper section which is to support the deck or platform to be centered on a predetermined line.

Another object of my invention is to provide a telescopicably adjustable pile, the upper deck supporting section of which, also serves as a sheath or shield for protecting the concrete which is later to be poured into the upper section and which forms an integral part of the concrete deck. 55

The invention possesses other advantageous features, some of which, with the foregoing, will be set forth at length in the following description where I shall outline in full that form of my invention which I have selected for illustration in the drawings accompanying and forming part of the present specification. In said drawings I have shown one form of reenforced concrete pile construction embodying my invention, but it is to be understood that I do not limit myself to such form since the invention as set forth in the claims may be embodied in a plurality of forms. 60 65 70

Referring to the drawings:

Figure 1 is a vertical section of my telescopicably adjustable pile, the upper section of which has been shown as supporting a deck 75 or platform.

Fig. 2 is a horizontal section taken on the line 2—2 of Fig. 1 and looking in the direction as indicated by the arrows.

Fig. 3 is a horizontal section taken on the line 3—3 of Fig. 1 and looking in the direction as indicated by the arrows. 80

My telescopicably adjustable pile comprises a driven pile 4. The length of this pile is so chosen so as to insure, that after being driven into the ground, its upper end will be sufficiently below the predetermined level of the deck or platform to obviate any necessity of cutting off or trimming its upper end. Telescopically engaged over the upper end of the driven pile 4 is an adjustable hollow cap or sleeve 5 preferably formed of concrete by precasting. After the upper end of the cap 5 has been adjusted to its proper predetermined height with respect to the deck or platform which it is to support, the clamps 7 are adjusted under its lower end and are secured to the driven pile by means of bolts 3. Moulding forms 9 on which concrete decks or platforms are to be poured may then be supported 95 100 105

on the upper end of the cap 5 by means of clamps 12 secured to the upper end of the cap 5 by means of bolts 8. It will be noted that there is a space 13 between the driven pile 4 and its telescoped cap 5. The purpose of this space 13 is to allow the upper end of the cap 5 to be centered with respect to any predetermined point relative to the deck. After the cap 5 has been centered and adjusted to the proper level, the space 13 is sealed with a cement grout 10. The concrete deck can then be poured into the form 6. At the time that the deck is poured, the space 11 above the upper end of the driven pile 4 is simultaneously poured with concrete thereby forming a leg integral with the deck. The length of the cap 5 is preferably chosen so that its lower end extends approximately to the water level at low tide.

20 It will thus be seen that by the above construction I have provided a pile which can be readily adjusted to any predetermined elevation without the necessity of trimming or cutting. The upper or supporting end of my pile can be readily centered with respect to any predetermined point on the deck or platform to be supported and the upper section of my telescopically adjustable pile simultaneously serves as a sheathing or protection 25 for the concrete leg which is moulded in the space 11.

I claim:

1. The method of extending a driven pile to a predetermined position which comprises 35 positioning an extension on said pile, said extension having a loose fit with respect to said pile, supporting said extension on said pile, and adjusting said extension vertically and laterally to said predetermined position.
- 40 2. That step in providing an extension to a driven pile which comprises telescoping a loose fitting extension over said pile and supporting said loose fitting extension at a desired position on said driven pile.
- 45 3. That step in providing a vertically and horizontally adjustable extension to a driven pile which comprises telescoping an extension over the top of said driven pile, positioning a clamp on said pile to support said extension on said pile, and adjusting said extension vertically and horizontally to a desired position.
- 50 4. The method of extending a previously driven pile to a predetermined exact elevation 55 for supporting a platform, which comprises positioning and vertically adjusting a suitable telescoping sleeve about the pile, and supporting the sleeve from the driven pile in its vertically adjusted position with its upper end in the predetermined exact elevation.
- 55 5. The method of extending previously driven piles to an exact elevation for cooperation with a horizontal deck or platform which comprises adding to the previously driven 60 piles suitable telescoping shells, adjusting the

shells vertically for exact elevation and positions, and fixing such positions by supporting the shells on the piles to receive plastic material while forming the platform.

6. In combination with a previously driven pile, a cast concrete casing telescopically positioned over the pile, and means for supporting the casing on the pile, said means being vertically adjustable and capable of being permanently fastened in a predetermined position of adjustment to support and position the casing.

In testimony whereof, I have hereunto set my hand.

HARRY E. SQUIRE.
